UNITED STATES PATENT OFFICE.

SAMUEL LEWIS VAN AKIN, JR., OF LIVERPOOL, NEW YORK.

TELEPHONE SYSTEM.

1,021,494.

Specification of Letters Patent. Patented Mar. 26, 1912.

Application filed February 2, 1910. Serial No. 541,588.

To all whom it may concern:

Be it known that I, SAMUEL LEWIS VAN AKIN, Jr., of Liverpool, in the county of Onondaga, in the State of New York, have invented new and useful Improvements in Telephone Systems, of which the following, taken in connection with the accompanying drawings, is a full, clear, and exact description.

This invention relates to certain improvements in telephonic instruments of a class set forth in my pending application No. 420,256, filed March 10, 1908.

The main object is to mount the transmitter and receiver upon and some distance to one side of the axis of a hollow swinging support carrying a circuit closer and suitable circuit connections passing through and concealed within the hollow support and connecting the circuit closer to the transmitter and to the receiver, so that the telephonic instruments may be swung to any convenient position for the operator through an arc of comparatively long radius without liability of twisting or kinking the circuit connections or otherwise straining any of the fastenings therefor, and at the same time permitting the circuits to be opened and closed by simply swinging the hollow support to different positions.

One of the specific objects of my present invention is to mount the receiver upon its hollow supporting arm, so as to be capable of oscillatory movement in any direction to readily adjust itself to the ear when in use.

A further object is to provide means for frictionally retaining the hollow support in either of its adjusted positions.

Other objects and uses relating to the specific parts of the device will be brought out in the following description:

In the drawings: Figure 1 is an elevation partly in section of my improved telephonic instrument showing the switch box and a portion of a desk or table upon which the apparatus is mounted but omitting the pedal operated and manually operated switches shown in Fig. 11. Fig. 2 is an enlarged front elevation partly in section of the instrument shown in Fig. 1 omitting the switch box. Figs. 3 and 4 are enlarged sectional views taken respectively on lines A—A and B—B, Fig. 2. Figs. 5 and 6 are perspective views of the hinge connections between the receiver and its supporting arm. Fig. 7 is an enlarged vertical sectional view

through the switch, switch-box and adjacent portion of the tubular standard showing also a portion of the supporting bed or table upon which these parts are mounted. Figs. 60 8, 9 and 10 are enlarged transverse sectional views taken respectively on lines C—C, D—D and E—E, Fig. 7. Fig. 11 is a diagrammatic view of the slip rings of the switch or circuit closer showing also a portion of the main line and local circuits including the receiver and transmitter.

In carrying out the objects stated a hollow arm —1— having an extension —2— carrying a transmitter —3— and receiver arm —4— is mounted for horizontal swinging movement upon a suitable support —5— which may be a desk, table top, standard or any other fixed member capable of sustaining the swinging member —1— and parts mounted thereon in operative position and permitting such arm to be shifted to any desired position about its axis.

As shown in the drawings, the hollow arm —1— consists of a tubular metal elbow, one arm of which extends horizontally, while the other arm is disposed in an upright position and passed through an opening —5'— in the support —5— and through an upright sleeve or tube —6— which is also passed 80 through the opening —5'—. Both of these tubular parts —1— and —6— extend some distance below the support —5— and are locked together for simultaneous rotation by a clamping bolt —7— which is passed diametrically through suitable apertures in the sleeve —6— and also through elongated slots —8— in the adjacent portion of the tubular arm —1—, thereby permitting a 85 limited longitudinal or vertical adjustment 90 of the arm —1— relatively to the sleeve —6— to bring the transmitter and receiver to the desired height most convenient for the operator. These two tubular members —1— and —6— are therefore locked together to 100 rotate as a unit and are journaled in suitable bearings —9— and —10— located respectively above and beneath the support —5— and held in place by clamping bolts —11—. A suitable buffer —12— of felt, rubber or 105 equivalent material is interposed between the base of the bearing —9— and upper face of the support —5— to form a muffler for the purpose of preventing reverberation of sound from the support —5— to the telephonic instruments. The bearing —10— is 110 made in the form of a cylindrical collar

encircling the sleeve —6— and provided with a recess —13— for receiving a flange —14— on said sleeve. Interposed between this collar and the under side of the support 5 —5— is the top —15— of a switch box —16— and a suitable buffer —17— of felt, rubber or similar material, the latter being interposed between the top —15— and under side of the support —5— for preventing 10 reverberation of sound from said support to the hollow member —1— and telephonic instruments carried thereby, the arm —1— being held against axial movement by collars —9'— and —10'—. Prior to the clamping 15 of the switch box to the under side of the table, the collar —10— is adjustably secured to the top of the switch box by means of screws —15'— sufficient clearance being left to permit a slight axial adjustment of the 20 collar.

A concavo-convex spring washer —18— is interposed between the base of the socket —13— and under side of the flange —14—, so that when the screws —15'— are properly adjusted the spring washer is slightly compressed between the base of the socket —13— and flange —14— thereby frictionally holding the rotary members —1— and —6— in their adjusted position, and at the 30 same time permitting them to be turned horizontally to bring the receiver and transmitter to any position about the swinging axis. Suitable washers —19— of leather or equivalent material containing a 35 lubricant are interposed between the opposite faces of the flanges —14— and adjacent faces of the top —15— and collar —10— respectively, so as to prevent excessive friction between the revolving members and fixed parts.

The hollow extension —2— is adjustable rotarily and axially in the adjacent end of the hollow arm —1— to permit the transmitter and receiver to travel through an arc 45 of longer or shorter radius or tilted bodily to any angle as may be desired, said extension being held in its adjusted position by a split clamping collar —20— or equivalent device. The outer end of the extension —2— is furcated forming opposite ears —21— for receiving between them a reduced portion —22— on the lower end of the receiver arm —4—, said ears —21— and reduced portion —22— being provided with 55 registering apertures for receiving a clamping bolt —23— which serves the double purpose of clamping the transmitter —3— to the extension —2— and also forms a pivotal connection between said extension and receiver arm upon which said receiver arm may freely swing. A nut —24— engages the outer end of the bolt —23— and adjacent ear or lug —21— and serves to frictionally bind said ears —21— against the 60 reduced portion —22— to hold the receiver 65

arm in its adjusted position. The main portions of the peripheries of the ears —21— are concentric with the swinging axis of the receiver arm —1— but their lower sides are provided with eccentric portions —25— forming limiting stops adapted to be engaged by shoulders —26— on said receiver arm for limiting the downward swinging movement of the latter and thereby preventing injury by cutting or 70 shearing against the circuit connections presently described, the base of the ears —21— forming a similar limiting stop for engaging the adjacent end of the opposite side of the receiver arm. 75

A receiver —27— is mounted for independent oscillatory movement upon the outer end of the receiver arm —4— and for this purpose is provided upon its rear with a U-shaped clamp —28— having spherical 80 sockets —29— for receiving and engaging opposite faces of a ball member —30—, the latter being secured to a cap —31— in the extreme outer end of the receiver arm —4—. The receiver —27— is therefore 85 connected to the arm —4— by a universal joint which permits a limited oscillation of said receiver in any direction to bring the ear piece into closer engagement with the ear while in use. In like manner the transmitter —3— is provided with an auxiliary mouth piece —3'— connected by a hollow universal joint —33— to the fronts of the 90 transmitter. 95

Circuit connections and circuit closer.— 100 A suitable circuit closer —34— together with the insulation —35— is secured to the periphery of the sleeve —6— within the switch box —16—, said circuit closer consisting of a series of slip ring segments 105 mounted on the insulation —35— and adapted to contact with a series of brushes —36—, the latter being mounted upon but insulated from a fixed arm —37— projecting downwardly from the collar —10—. 110 This circuit closer is connected, in a manner hereinafter described, to the transmitter —3— and receiver —27— by circuit connections —38— and —38'— which are passed through and concealed within the 115 arms —1— and —4— and extension —2—, leaving only a slight portion thereof exposed at the junction of said receiver arm with the extension and also at a point near the receiver as shown in Fig. 2, although in 120 Fig. 7 the circuit connections for the receiver enter directly into said receiver from the interior of the hollow arm —4—. The terminal ends of the circuit connections —38— and —38'— where they emerge 125 through the lower end of the tubular arm —1— are connected to segmental terminals —39— on the insulating sleeve —35—, so as to rotate with the arm —1— and sleeve —6—, thereby preventing any possibility of 130

twisting, kinking or otherwise straining the circuit connections or their fastenings as the supporting arm —1— for the receiver and transmitter is swung laterally.

- 5 In Fig. 12 is shown diagrammatically the circuit connections for the receiver, transmitter and circuit closer and also a portion of the main line and additional switches for opening and closing the primary and secondary circuits of the induction coil, hereinafter described. The circuit closer comprises a series of, in this instance four, slip rings —A—, —B—, —C— and —D—, which together with the terminal segment —39— are 70 coaxially mounted for simultaneous rotation with the sleeve —6— and supporting arm —1—. The conducting segments of each slip ring are electrically connected to each other and to one of the terminal segments —39—, as clearly shown in Fig. 12, so that the wires —38— leading from the transmitter are electrically connected respectively to the conducting segments of the slip rings —A— and —B—, while the conducting wires —38'— leading from the receiver are electrically connected respectively to the conducting segments of the slip rings —C— and —D—. When the conducting segments of the circuit closer are brought 80 into contact with their respective brushes —36—, the receiver —27— is electrically connected in series with a condenser —E— across the main line circuit —F— through the medium of a switch —G— which is normally in contact with a terminal —g— forming a part of such circuit. This circuit leads from one side of the main line —F— through wire —40— to one side of the condenser —E— and thence by wires —41— and —42— to the switch —G— and terminal —g— through wires —43— and —44— to the conducting segments of the ring —C— and thence by wire —45— to one of the segmental terminals —39— which is connected 90 by one of the wires —38'— to the receiver, the other receiver wire being connected to another one of the terminals —39— and thence by wire —46— to the conducting segments of the slip ring —D— which in turn is connected by wires —47— and —48— to the other side of the main line —F—. A retard coil —H— is connected across the receiver circuit wires —42— and —43— and is adapted to be connected in series with the receiver in a manner presently described. The switch —G— may be moved out of contact with the terminal —g— and into contact with another terminal —g'— by any suitable operating device, as —G'—, operable at will, said operating member being also employed to simultaneously operate a normal open switch —I— into contact with a terminal —i—. This terminal —i— is electrically connected to one pole of a source 95 of electric energy as a battery —J—, the other pole of said battery being connected by wires —49— and —50— to the conducting segments of the slip ring —B— when in contact with the corresponding brush —36—, said conducting segment being connected by a wire —51— to one of the terminal segments —39— which in turn is connected to one of the transmitter wires —38—, the other transmitter wire being electrically connected to a different terminal segment 100 —39— and thence by wire —52— to the conducting segments of the slip ring —A—. When these conducting segments of the ring —A— are in contact with corresponding brush —36—, they are electrically connected by a wire —53— to one side of the primary winding —54— of an induction coil —K—, the other side of said primary coil being connected by wires —55— and —56— to the switch —I— which is now in contact with the terminal —i— thus completing the circuit through the primary winding of the induction coil. At the same time that the switch —I— is forced into contact with the terminal —i—, the switch —G— is brought 110 into contact with the terminal —g'— connecting the retard coil —H— in series with the receiver as follows: From one side of the secondary coil, as —57—, by wires —58— and —59— through terminal —g'— and switch member —G— thence by wires —42— and —60— to one side of the retard coil —H— thence from the opposite side of the retard coil by wires —61— and —44— to the conducting segments of the slip ring —C— which are connected to the receiver through the medium of the wires —38'—, terminal segments —39— and wire —45—, one of the segments —39— being connected by a wire —46— to the conducting segments 120 of the slip ring —D— which when in contact with the corresponding brush —36— are connected by wires —47— and —62— to the opposite side of the secondary coil. Or on the other hand, tracing the circuit from the main line when the conducting members of the slip rings are in contact with their respective brushes, the current passes through one side of the main line from the wire —40—, condenser —E—, wires —41— and —60— through the retard coil and wires —61— and —44—, slip ring —C— through the receiver and return through the wire —46—, slip ring —D— and wires —47— and —48— to the other side of the main line. 125 The operating member —G'— may be of any suitable construction capable of being operated at will either by hand or foot and is shown as consisting of a pedal, while at the right of the same figure I have shown the same switch as adapted to be operated by a manual —M— and in which the switch members and terminals are shown as connected by dotted lines to the same binding posts as those to which the corresponding 130

terminals and switch members are connected. It is to be understood, however, that aside from the mounting of the circuit closer upon the rotary arm —1— so as to open and close the several circuits by the mere rotation of such arm, the details of construction may be varied considerably without departing from the spirit of my invention, therefore I do not limit myself to the exact 10 construction and arrangement as shown and described.

What I claim is:

1. In a telephonic system, a rotary support, a hollow receiver arm mounted on the support, a receiver mounted upon the receiver arm, a slip-ring on the rotary support and circuit connections between the slip-ring and receiver and extending through the receiver arm.
2. In a telephonic system, a rotary tubular support and a hollow receiver arm pivoted thereto, a receiver on said arm, a transmitter on the support at its junction with the receiver arm, ball and socket connections between the receiver and arm whereby the receiver may be oscillated in any direction, slip-rings on the support and circuit connections leading from the slip-rings to the transmitter and to the receiver.
3. In a telephonic system, a hollow arm mounted for rotary movement, a transmitter and a receiver carried by said arm, a slip ring rotating with the arm, a brush contacting with the ring, and circuit connections for the receiver and transmitter passed through said arm, one at least of said connections being connected to the slip ring.
4. In a telephonic system, a hollow arm mounted for horizontal rotary movement, a transmitter carried by the arm, a slip ring rotatable with said arm, a brush in contact with the slip ring, and circuit connections between the slip ring and transmitter passing through the hollow arm.
5. In a telephonic system, a hollow arm mounted for rotary movement, a transmitter mounted on the arm, a hollow receiver arm

mounted for swinging movement upon the first named arm, a receiver on the receiver arm, slip rings rotating with the first named arm, brushes contacting with the slip rings, and circuit connections passing through the hollow arms and connecting the slip rings to the transmitter and to the receiver.

6. In a telephonic system, a supporting bed, a hollow arm passing through the bed and mounted thereon for rotary movement, telephonic instruments carried by the arm above the bed, slip-rings rotating with the arm below the bed, and circuit connections between the slip-rings and said instruments and passing through the hollow arm.

7. In a telephonic system, a supporting bed, a hollow arm passing through the bed and mounted thereon for rotary movement, telephonic instruments carried by the arm above the bed, a circuit closer rotating with the arm below the bed, circuit connections between the circuit closer and said instruments and passing through the hollow arm, and mufflers interposed between the bed and bearings for the arm to prevent reverberation of sound from the bed to the instruments.

8. In a telephonic system, in combination with a table top and vertical journal bearings thereon, a hollow arm mounted for rotary movement in said bearings and extending through the table top, said arm having a lateral offset above the table top, a transmitter mounted on said arm, a hollow receiver arm hinged to the transmitter arm, a receiver on the receiver arm, slip-rings mounted on the first named arm below the table top, and circuit connections passing through the hollow arms and connecting the slip-rings to the receiver and to the transmitter.

In witness whereof I have hereunto set my hand on this 22nd day of January 1910.

SAMUEL LEWIS VAN AKIN, JR.
